M. LAVIGUE.
MOLDING AND METAL FASTENER FOR SASHES AND WINDOW PANES.
APPLICATION FILED FEB. 2, 1921.

1,389,057.

Patented Aug. 30, 1921.

UNITED STATES PATENT OFFICE.

MOSES LAVIGUE, OF HOLYOKE, MASSACHUSETTS.

MOLDING AND METAL FASTENER FOR SASHES AND WINDOW-PANES.

1,389,057.

Specification of Letters Patent. Patented Aug. 30, 1921.

Application filed February 2, 1921. Serial No. 441,952.

To all whom it may concern:

Be it known that I, MOSES LAVIGUE, a citizen of the United States, residing at Holyoke, in the county of Hampden and State of Massachusetts, have invented certain new and useful Improvements in Molding and Metal Fasteners for Sashes and Window-Panes, of which the following is a specification, reference being had to the accompanying drawings.

Putty used for fastening window panes in the rabbets of sashes dries and then crumbles and falls out, thereby loosening the pane, which will eventually fall out, thereby necessitating the reglazing of the sashes. Furthermore when the pane of glass becomes broken, necessitating the placement of a new glass, the putty must be cut away, which must be accomplished from the exterior of the building, or the sash removed, by taking out the guide strips, to permit the reglazing of the sash after it has been removed from the frame. While accomplishing this the window is opened, which chills off the room. It is the purpose of the present invention to overcome these disadvantages, by providing an improved molding and metal fastening strip, detachably fastened to the sash, so that the broken pane may be very easily and quickly removed, and a new one placed in position, avoiding the use of putty, and at the same time permitting the work to be accomplished from the interior of the room.

Another purpose involves the use of molding, which may be lifted from the channel of the sash rail, by means of a suitable tool, such as a screw driver or chisel whereby the pane of glass may be easily and very quickly removed.

Still another purpose consists in the provision of a metal strip adjacent the exterior of the sash employed instead of the putty, and provided with a weather proof strip of any suitable material, such as rubber, felt, asbestos or the like, preferably rubber, to insure a tight fitting joint in order to preclude the weather.

While the design and construction at present illustrated and set forth is deemed preferable, it is obvious that as a result of a reduction of the invention to a more practical form for commercial purposes, the invention may be susceptible of changes, and the right to these changes is claimed, provided

they are comprehended within the scope of 55 what is claimed.

The invention comprises further features and combinations of parts, as will be herein-after set forth, shown in the drawings and claimed:

In the drawings:-

Figure 1 is a sectional view through a portion of a window sash showing the improved molding and fastening strip as applied, holding the pane of glass in position.

Fig. 2 is a perspective view of one corner of the sash, showing the molding adjacent the interior of the pane of glass and the sash rails.

Fig. 3 is a detail perspective view of one corner of the exterior of the sash, showing the metal fastening strips.

Fig. 4 is an enlarged detail view of a portion of one of the metal fastening strips constructed in accordance with the invention.

Fig. 5 is a detail perspective view of a portion of a metal fastening strip, disclosing the same from another angle.

Referring more especially to the drawings, 1 designates a window sash as a whole, 80 and 2 denotes the pane of glass. Certain of the faces of the side, top and bottom sash rails are provided with channels 3, in which wood moldings 4 engage.

Secured to the same faces of the sash rails are metal strips 5. Each metal strip consists of a body portion 6, which is fastened by screws or the like 7 to the sash rail, particularly adjacent the outer portion of the sash. Also said strip has flanges 8 and 9. 90 The flange 8 is bent inwardly at an angle to the body portion and assumes an inclined position, and constitutes means for holding the pane of glass in place. The edge of the flange 8 and its underface have a weather proof binding or strip 10, of rubber, felt, asbestos or the like, preferably rubber secured thereto by any suitable means, preferably cement or vulcanizing. This weather

proof strip contacts with the outer face of the pane of glass, and not only cushions the flange 8, but also precludes the weather. The flange 9 extends into the channel 3 and is provided with a plurality of slots or openings 11, and the tongues intermediate these openings or slots are sufficiently yieldable, to bear against the molding 4, thereby so coöoperating with the molding, as to not

only hold the same in the channel 3, but also to hold the upper flange portion 12 in contact with the inner face of the pane of glass. The edge of the flange 12 is slightly beveled, 5 so that the margin 13 of the flange will engage the inner face of the pane of glass immediately opposite the weather proof strip. In order that the flange 9 may engage the molding 4, the outer face of the molding 10 at a point below the flange 12 is arcuate in cross section as shown at 14, so that the flange 9, which is also arcuate in cross section, may conform therewith. It will be noted that the arcuate face 14 of the molding 15 terminates in an extension 15, which engages partially under the curved edge portion 16 of the flange 9, thereby acting to securely lock the molding 4 in position. This molding may have any suitable exterior 20 configuration in order to constitute a sash of finished appearance. The inner face of the molding 4 is inclined as shown at 17 relatively to one wall of the channel 3, so as to give the molding sufficient movement play, to permit the molding to be lifted from the channels, when it is desired to replace the old pane with a new one. It will be noted that when the molding is inserted in the channel, it is necessary to apply 25 a certain amount of pressure, in order to cause the curved edge portion 15 to engage under the curved edge portion 16, and in order to accomplish this result it is necessary to permit of a certain amount of play between one wall of the channel and the molding. Also in order to accomplish 30 this result, the flange 9 extends outwardly, allowing the curved portion 15 to engage the outer surface of the flange 9, and extend below the edge thereof. The inner face of the molding 14 has a groove 18, which may be engaged by means of a suitable tool, such as a screw driver, chisel or the like, so that by fulcrumming the tool on 35 the edge of the sash, the molding 14 may be lifted from the channel. When the molding is removed, it is possible to move the pane of glass from the sash to the interior of the room, while a new pane of glass is 40 being placed in position.

Where the metal strip 6 is carried by the rails of the sashes, a suitable packing or weather proof strip 19 is fastened in place. This strip 19 may be constructed of any 45 suitable material, such as rubber, felt, asbestos or the like, and constitutes means to preclude the weather. Where the flange 8 of the metal strip 6 is bent from the body of the strip, the metal strip is bent outwardly as shown at 10', in order to overlie the outer marginal corner, thereby insuring 50 precluding the weather.

The invention having been set forth, what is claimed as being useful is:

65 1. In a window pane fastener, the com-

bination with a sash rail having a channel, of a metal fastening strip secured to said rail and having its outer portion bent inwardly to form a flange provided with weather proof material to engage the outer 70 face of the pane of glass, which glass is mounted upon the surface of the strip, a molding seated in the channel and having a beveled outer face adjacent the inner face of the pane of glass, whereby the outer 75 edge of the molding may bear against the pane of glass immediately opposite the weather proof strip, said metal strip having means extending into the channel, to hold the molding in position.

2. In a device for the purpose indicated, a sash rail having a channel, a window pane, means carried by the sash rail and engaging the outer face of the pane of glass to prevent outward movement of the pane of glass, a molding engaging said channel and having a flange engaging the inner face of the pane of glass, said first means having means extending into the channel and operatively connecting with the molding, to 80 not only hold the molding in place, but also to insure tightening the glass against the outer holding means.

3. In a device for the purpose indicated, a sash rail having a channel near its inner portion, a plate secured to the sash rail and having means adjacent the exterior of the sash to coöperate with the outer face of a glass pane, a molding engaging said channel and provided with a portion engaging the inner face of the glass and binding the glass against said means, said molding having an outer arcuate face, said plate having an arcuate yieldable flange extending into the channel and engaging the arcuate face of the molding, to assist in holding the molding in position.

4. In a device for the purpose indicated, a sash rail having a channel near its inner portion, a plate secured to the sash rail and having means adjacent the exterior of the sash to coöperate with the outer face of a glass pane, a molding engaging said channel and provided with a portion engaging the inner face of the glass and binding the glass against said means, said molding having an outer arcuate face, said plate having an arcuate yieldable flange extending into the channel and engaging the arcuate face of the molding, to assist in holding the molding in position, said arcuate outer face of the molding terminating in a part extending below the flange of the plate, further assisting in holding the molding in contact with the glass pane.

5. In a device for the purpose indicated, a sash rail having a channel near its inner portion, a plate secured to the sash rail and having means adjacent the exterior of the sash to coöperate with the outer face of a 130

glass pane, a molding engaging said channel and provided with a portion engaging the inner face of the glass and binding the glass against said means, said molding having an outer arcuate face, said plate having an arcuate yieldable flange extending into the channel and engaging the arcuate face of the molding, to assist in holding the molding in position, and a weather proof strip placed between the plate and the sash rail, to insure precluding the weather.

6. In a device for the purpose indicated, a sash rail having a channel near its inner portion, a plate secured to the sash rail and having means adjacent the exterior of the sash to coöperate with the outer face of the glass pane, a molding engaging said channel and provided with a portion engaging the inner face of the glass and binding the glass against said means, said molding having an outer arcuate face, said plate having an arcuate yieldable flange extending into the channel and engaging the arcuate face of the molding, to assist in holding the molding in position, said arcuate outer face of the molding terminating in a part extending below the flange of the plate, further assisting in holding the molding in contact with the glass pane, and a weather proof strip placed between the plate and the sash rail, to insure precluding the weather, said molding having a groove

placed on its inner face to be engaged by a tool for lifting the molding out of the channel.

35

7. In a device for the purpose indicated, the combination with a sash rail having a channel, of a molding seated in said channel and having means engaging the inner face of a glass pane, a metal fastening strip secured to said rail and having its outer portion provided with abutment means, with which the pane engages, the inner part of the metal fastening strip having means extending into the channel and engaging and holding the molding in the channel.

40

8. In a device for the purpose indicated, a sash rail having a channel, a molding seated in said channel and having means engaging the inner face of a glass pane, said molding having a curved face, a metal fastening strip secured to said rail and having its outer portion provided with abutment means, with which said pane engages, the inner portion of the metal fastener having a yieldable flange corresponding in shape with and engaging said curved face of the molding, to retain the molding in the channel.
